TIE CONSTRUCTION

Isaac Marinsky, Providence, R. I.

Application March 8, 1938, Serial No. 194,572

1 Claim. (Cl. 2—146)

My present invention relates to cravats and more particularly to a novel construction for a tie.

The principal object of the present invention is to provide a tie which can be readily opened for cleaning, washing and ironing.

Another object of my invention is to provide a tie which will tend to retain its shape during use, and which will not wrinkle readily.

With the above and other objects and advantageous features in view, my invention consists of a novel arrangement of parts as more fully disclosed in the detailed description following, in conjunction with the accompanying drawings, and more specifically defined in the claim 18 appended thereto.

In the drawing,

Fig. 1 is an elevation of a tie embodying the present invention, the closure fastener being closed;

20 Fig. 2 is a similar view, the closure fastener being open;

Fig. 3 is a plan view of a form for shaping or drying a tie after washing and cleaning;

25 Fig. 4 is a horizontal section taken along line 4—4 of Fig. 1;

Fig. 5 is a fragmentary view of a modified form, the closure fastener being open;

Fig. 6 is a similar view of another modified form;

30 Fig. 7 is a section of the form shown in Fig. 6, the closure fastener being closed;

Fig. 8 is a section of the form shown in Fig. 5 partially opened.

Referring more in detail to the drawing illustrating my invention, the numeral 10 designates a conventional form of men's necktie having a base portion 11 comprising a comparatively wide end tapering toward a narrow neck portion which in turn tapers in the opposite direction to a slightly wider portion and two flap portions 12 and 13 integral therewith and correspondingly shaped and having longitudinal edges 14 and 15 adapted to be fastened together to complete the tie structure.

45 The standard form of tie is sometimes lined with a slightly coarser or stiffer material to give the tie body and help it retain its shape, the tie being conventionally cut to shape and folded over and stitched along the edges to form a tube.

50 I prefer to provide the edges 14 and 15 with a slide fastener or zipper 16 of the separable type, whereby the edges are locked together continuously throughout their length. The oppositely disposed teeth on a slide fastener or zipper are normally attached to a tape of uniform width

which is sewed to the material. However, I prefer a zipper fastener 16 which is attached to a tape 17 shaped to conform to the contour of the tie shown in Fig. 10. The excess portion of the tape 17 thus forms an inner lining for the tie 5 and no further lining is therefore necessary. The tape 17 helps to retain the shape of the tie, and if it becomes necessary to wash, clean or iron the same, it is merely necessary to open the zipper 16, as shown in Fig. 2. This facilitates 10 ironing, cleaning or washing. After cleaning, washing or ironing it may be preferable to place the tie on a form 18 (Fig. 3) of any suitable material and close the slide fastener 16 so that it will dry and set itself into proper shape. The 15 edges of the form may be bevelled to insure proper creasing.

In the form shown in Fig. 5 the tie 19 is provided with a slide fastener 20 of standard construction having a tape 21 of uniform width and a conventional type separate lining 22. The lining 22 is sewed to one flap of the tie as shown in Figs. 5 and 8. In this form of construction it is not necessary to have special slide fastener tapes, and the lining 22 is swung out of the way during 25 the ironing operation without displacement or loss.

Of course the slide fastener, while extremely flexible affords a certain stiffness and resiliency and on cheaper constructions or stiffer materials it is feasible to omit the lining, as shown in Fig. 6, in which a tie 23 is merely provided with a conventional slide fastener 24 and with tape of uniform width 25.

As can readily be seen from the above description the tie of the present invention is easy and economical to fabricate and assemble and is admirably adapted for its intended function. The slide fastener can easily be opened to facilitate 40 cleaning, washing and ironing of the tie, while the tape attached to the fastener provides a suitable lining which helps to retain the shape of the tie and to decrease wrinkling. Moreover, the use of a longitudinal closure member as an integral portion of the tie prevents slippage or sliding of the tie knot, and ensures a perfectly formed and positioned tie at all times.

While I have described specific conventional embodiments of my invention and specific arrangements for mounting the separable fasteners therein, it is obvious that changes may be made to suit the requirements for different form of ties, and that the invention may be applied to similar objects such as scarfs, without departing from 50 55

the spirit and scope of the invention as defined in the appended claim.

I claim:—

In a tie construction, a tie body having a base portion and two flap portions integral therewith, said flap portions having longitudinal edges adapted to be juxtaposed, and a slide fastener

for securing said edges together continuously throughout their length, said slide fastener comprising a securing tape secured to each of said longitudinal edges and positioned within the flap portions to form the lining of the tie when said flaps are closed. 5

ISAAC MARINSKY.
